(57) **CLAIM**

I claim the ornamental design for a portable mat for musical instruments, as shown and described.

DESCRIPTION

FIG. 1 is a front view of a portable mat for musical instruments showing my new design; the design shown in a folded orientation;

FIG. 2 is a perspective view thereof; the design shown completely unfolded;

FIG. 3 is a perspective view thereof; the design shown as used beneath a part of a drum; and,

FIG. 4 is another perspective view thereof; the design shown as used beneath a part of a drum.

The broken lines in FIG. 3 and FIG. 4 showing a drum are for the purpose of illustrating environmental structure only and form no part of the claimed design. The rear view of the design is not shown, since it is not visible in its end use. The rear view forms no part of the claimed design.
